WALL HANGER FOR FLOWER POTS OR THE LIKE

Ray E. Troendly, Elkton, Oreg.

Filed Apr. 30, 1959, Ser. No. 55,715

Term of patent 14 years

(Cl. D35—3)

Fig. 1 is a front perspective view of a wall hanger for flower pots or the like embodying my new design, with a flower pot being shown in broken lines for illustrative purposes only;

Fig. 2 is a view similar to Fig. 1, but with the flower pot removed;

Fig. 3 is a left side elevational view thereof; and

Fig. 4 is a front elevational view thereof.

I claim:

The ornamental design for a wall hanger for flower pots or the like, as shown and described.
